(57) **CLAIM**

The design for a fitter glove, as shown and described.

DESCRIPTION

FIG. 1 is a plan view of a back side for a fitter glove showing my new design; and,

FIG. 2 is a plan view of a palm side thereof.

The design consists of the features of pattern and configuration of the entire glove shown in the drawings. The most significant feature of the design is the appearance of the cuff having tapered sides which overlap. The dashed lines are features of ornamentation which form part of the design.
